[57] **CLAIM**

The ornamental design for a reconfigurable toy boat, substantially as shown and described.

DESCRIPTION

FIG. 1 is a perspective view of a reconfigurable toy boat showing my new design;
FIG. 2 is a right side elevational view thereof, the side opposite being a mirror image;
FIG. 3 is a top plan view;
FIG. 4 is a bottom plan view;
FIG. 5 is a front elevational view;
FIG. 6 is a rear elevational view;
FIG. 7 is a perspective view of the design shown in FIGS. 1 through 6 in a toy robot reconfiguration;
FIG. 8 is a right side elevational view thereof, the side opposite being a mirror image;
FIG. 9 is a top plan view;
FIG. 10 is a bottom plan view;
FIG. 11 is a front elevational view; and
FIG. 12 is a rear elevational view.
